(No Model.)

O. S. MOSS.
CARBON HOLDER FOR ARC LIGHTS.

No. 591,486.

Patented Oct. 12, 1897.

WITNESSES:

ATTORNEYS.

UNITED STATES PATENT OFFICE.

OSCAR S. MOSS, OF SYRACUSE, NEW YORK.

CARBON-HOLDER FOR ARC-LIGHTS.

SPECIFICATION forming part of Letters Patent No. 591,486, dated October 12, 1897.

Application filed January 28, 1897. Serial No. 621,054. (No model.)

To all whom it may concern:

Be it known that I, OSCAR S. MOSS, of Syracuse, in the county of Onondaga, in the State of New York, have invented new and useful 5 Improvements in Carbon-Holders for Electric Lights, of which the following, taken in connection with the accompanying drawings, is a full, clear, and exact description.

This invention relates to improvements in 10 carbon-holders for electric lamps.

My object is to produce a carbon-holder which will automatically center the carbon when, for instance, the same is warped or crooked, so that it will be impossible to get 15 out of alinement with the carbon in the lower holder; also one in which as many parts as possible of the upper and lower holders are interchangeable, for I have found by practical experience a great deal of difficulty is 20 experienced in maintaining the trim of the lamp, for the reason that if it is not trimmed straight—that is, if the two carbons are not held in alinement when the machine flashes or the current is temporarily off—the upper 25 carbon will slip by the lower one to such an extent that the automatic mechanism provided for raising it will be unable to lift it sufficiently to start again, and it will therefore be necessary to require the attention of 30 the attendant before it can again be used; and to that end my invention consists in the several new and novel features of construction and operation hereinafter described, and which are specifically set forth in the claims 35 hereunto annexed. It is constructed as follows, reference being had to the accompanying drawings, in which—

Figure 1 shows a side view of the lower part of an electric lamp, showing my improved 40 carbon-holder. Fig. 2 is a vertical section on line X X, Fig. 1. Fig. 3 is a top plan view of the upper-carbon holder. Fig. 4 is a top plan view of the lower-carbon holder. Fig. 5 is an outside view of the bracket which supports the lower-carbon holder. Fig. 6 is a top view of the lower supporting-bracket. Fig. 7 is a view of the clamp which holds the 45 carbon and the holder together. Fig. 8 is an inner view of the top of the upper holder. Fig. 9 is a view of the outer face of the interchangeable side pieces.

Similar letters and figures of reference indicate corresponding parts.

a are the vertical standards of the holder, having a cross-piece *b* at the lower end and 55 in which there is a central opening *b'*, through which the lower carbon may pass.

Referring now to the upper-carbon holder, *c* is a body having a threaded opening in the top *c'* for reception of the lamp-rod and extending laterally, as shown at *d*, for the purpose of affording a shield or housing for the clamp and terminating in a projection *d'*, having its inner face convexed, as shown at *f'* in Fig. 8.

e is a side piece having one face concaved and adapted to receive the carbon *e'*, the opposite side being provided with a concaved surface *f*, adapted to engage with the convexed bearing *f'* upon the inner edge of the 70 top piece *c*. *g* is a ring having a threaded opening upon one side adapted to receive a thumb-screw *g'*, the whole forming a clamp to hold the carbon and side pieces *e* to the lower extremity of the top piece *c*. The side 75 pieces *e* are provided with laterally-extending lugs *h*, so as to prevent them from slipping down below the ring *g*, and the lower extremity is provided with lugs *h* for the purpose of holding the ring *g* in position.

Referring now to the lower holder, 1 is a bracket constructed substantially as shown, having a projecting top 2, forming a housing, a convexed inner face 3, forming a bearing for the concaved side *f* of the side piece, and 85 the lower projecting T-foot.

5 is a V-shaped bracket constructed substantially as shown and having a threaded opening 6, adapted to receive a thumb-screw 7. The bracket 5 rests upon the T-shaped 90 foot 4, as shown in Fig. 1, embracing the lower carbon, and thumb-screw 7 engages with the cross-bar *b*, thereby holding the bracket 1 in the position shown in the drawings. The clamp holds the parts together the 95 same as shown in the upper holder.

Having described my invention, what I claim, and desire to secure by Letters Patent, is—

1. A carbon-holder comprising a top adapted to receive a lamp-rod, and having an inner convex bearing-surface, a side piece

having both faces concaved, one of which is adapted to engage with the carbon, and the other with the inner face of the top, and means for holding them and the carbon together.

2. A carbon-holder comprising a top adapted to receive a lamp-rod, and having a laterally-projecting housing, an inner convex bearing-surface, a side piece having both faces concaved, one of which is adapted to engage with the carbon and the other with the inner face of the top, and means for holding them and the carbon together.

3. A carbon-holder comprising a top adapted to receive a lamp-rod, and having a laterally-projecting housing, a lower extension provided with lugs, said extension having an inner convex bearing-surface, a side piece having laterally-extending lug or lugs and

both faces concaved, one of which is adapted to engage with the carbon and the inner face of the top, and means for holding them and the carbon together as set forth.

4. A carbon-holder comprising a bracket having a lower extending foot, and means for securing said foot to the cross-piece of the lamp, said bracket having a portion of its upper inner face convexed, a side piece having its faces concave and adapted to engage with the carbon and the inner face of the bracket, and means for holding them and the carbon together as set forth.

In witness whereof I have hereunto set my hand this 18th day of December, 1896.

OSCAR S. MOSS.

In presence of—

MARY A. FRANKLIN,
HOWARD P. DENISON.
